UNITED STATES PATENT OFFICE.

JOSIAH LETCHWORTH, OF BUFFALO, NEW YORK.

DESIGN FOR COCKEYE.

Specification forming part of Design No. 6,152, dated September 24, 1872.

To all whom it may concern:

Be it known that I, JOSIAH LETCHWORTH, of the city of Buffalo, in the county of Erie and State of New York, have invented or produced a new and original Design for Cockeye for Harness, of which the following is a specification:

The essential feature of my design is the peculiar and symmetrical form of the cockeye, which results from making the ends of the loop to which the tug is attached of semicircular form, and connecting directly therewith the loop, which engages with the whiffletree without any intervening neck or shank.

In the accompanying drawing, Figure I is an elevation of my new design for cockeye. Fig. II is an elevation at right angles to Fig. I; and Fig. III is a vertical section on line *x* *x*, Fig. I.

Like letters of reference designate like parts in each of the figures.

A represents the loop of the cockeye, which engages with the whiffletree, and B the loop, through which the trace or tug passes. The

loop B is made in the form of a link, with the side bars *b* *b*¹ parallel and the connections *b*² at the ends semicircular, as clearly shown in Fig. I. The metal forming the loop B is round in cross-section, except the central cross-bar *b*, which is flattened on opposite sides at its junction with the loop A. The eye of the loop A is of egg-shape, the metal of the outer portion of the loop being of greater thickness, while the inner end connects directly with the cross-bar *b* without any intervening neck, as shown in the drawing. This form of the loop A and the semicircular ends of the loop B render the device compact and symmetrical, thereby greatly improving the appearance thereof.

I claim as my invention—

The design of the loop B of cockeye, herein shown and described.

JOSIAH LETCHWORTH.
